UNITED STATES PATENT OFFICE

103,729

DESIGN FOR A BOTTLE

Louis A. Leppke, Omaha, Nebr.

Application January 28, 1937, Serial No. 67,317

Term of patent 14 years

To all whom it may concern:

Be it known that I, Louis A. Leppke, a citizen of the United States, residing at Omaha, in the county of Douglas and State of Nebraska, have invented a new, original, and ornamental Design for a Bottle, of which the following is a specification, reference being had to the accompanying drawing, forming a part thereof.

I claim:

The ornamental design for a bottle substantially as shown.

LOUIS A. LEPPKE.
